UNITED STATES PATENT OFFICE.

BERNICE PIER, OF NOKOMIS, ILLINOIS.

BOUDOIR CAP.

Application filed September 4, 1926. Serial No. 133,593.

The present invention relates to caps and more particularly to ladies' boudoir caps and an important object of the invention resides in the provision of a boudoir cap which may be placed in a relatively flat position whereby the entire surface of the cap may be easily accessible when it is desired to iron the same during the laundering process.

Another very important object of the invention resides in the provision of a boudoir cap of this nature with a simple construction that is attractive in appearance, cheap of manufacture, and comfortable when it is fixed upon the head of the wearer.

With these and numerous other objects in view as will appear as the description proceeds, the invention resides in certain novelties of construction, and in the arrangement of parts as will be hereinafter more fully described and claimed.

In the drawing:

Figure 1 is a side elevation of the cap embodying features of my invention,

Figure 2 is a plan view of the cap in a relatively flat position,

Figure 3 is another side elevation thereof.

Referring to the drawing in detail, it will be seen that the body 5 is made up of an oblong piece of cloth having its side edges towards one end slightly converging. A relatively narrow cuff 6 is provided at said end of the body 5 and a relatively wide cuff 7 is provided at the other end thereof. These cuffs extend transversely of the body and are formed to be attractive in appearance. A pair of spaced buttonholes 8 are arranged along each edge of the body and the top 7 as is indicated at 8. A single buttonhole 9 is provided intermediate the ends of each longitudinal edge of the body. A pair of buttons 10 and 11 are arranged along each longitudinal edge of the body adjacent the cuff end 6.

When the top is in the relatively flat position shown in Fig. 2 it is folded over upon itself so that the buttons 11 are engaged in the end openings 8 and the buttons 10 engaged in the other end openings 8. The openings 9 are then engaged over the buttons 10 thus completing the boudoir cap in its position to be placed over the head.

It will be seen that the structure is exceedingly simple, inexpensive to manufacture, and yet may be made very attractive in appearance. No skill is required in the manipulation of the cap to its different positions and thus the laundering of the cap is made relatively easy.

While I have described what I believe to be the most desirable embodiment of my invention, it is obvious that many of the details may be varied without in any way departing from the spirit of my invention, and I therefore do not limit myself to the exact details of construction herein set forth nor to anything less than the whole of my invention limited only as hereinafter claimed.

Having thus described my invention what I claim as new is:

A boudoir cap having an elongated body provided on each longitudinal edge adjacent one end with a pair of longitudinally placed button holes, and a button hole at the intermediate portion of the body, and a pair of longitudinally spaced buttons on each longitudinal edge of the body adjacent the other end thereof, said buttons adapted to pass through the end button holes and one of the buttons on each longitudinal edge of the body being adapted to pass through the respective intermediate button hole.

In testimony whereof I affix my signature.

BERNICE PIER.
